CLAIM

The ornamental design for an electronic device with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a front view of an electronic device with graphical user interface showing the claimed design. The peripheral dashed broken lines depict a display screen or portion thereof, and form no part of the claimed design. The claimed design is illustrated within the dashed line rounded rectangle; the half-tone portion between the peripheral dashed broken lines and the dashed line rounded rectangle forms no part of the claimed design.
